US0D1108536S

(12) **United States Design Patent** (10) Patent No.: **US D1,108,536 S**
(45) Date of Patent: ** Jan. 6, 2026

(54) **PRINTER**

(71) Applicant: **BROTHER INDUSTRIES, LTD.**,
Nagoya (JP)

(72) Inventors: **Hiromitsu Tanaka**, Nagoya (JP);
Kazuki Nakano, Iwakura (JP);
Yukihiko Sato, Nagoya (JP); **Yoshihiro Okamoto**, Komaki (JP); **Hiroaki Shigeno**, Nagoya (JP)

(73) Assignee: **BROTHER INDUSTRIES, LTD.**,
Nagoya (JP)

(**) Term: **15 Years**

(21) Appl. No.: **29/918,891**

(22) Filed: **Nov. 30, 2023**

(30) **Foreign Application Priority Data**

Jun. 2, 2023 (JP) ..... 2023-011298 D

(51) LOC (15) Cl. **14-02**

(52) U.S. Cl.

USPC **D18/50**

(57) **CLAIM**

The ornamental design for a printer as shown and described.

DESCRIPTION

FIG. 1 is a perspective view of the printer;
FIG. 2 is a front elevational view thereof;
FIG. 3 is a rear elevational view thereof;
FIG. 4 is a left-side elevational view thereof;
FIG. 5 is a right-side elevational view thereof;
FIG. 6 is a top plan view thereof; and,
FIG. 7 is a bottom plan view thereof.

The evenly spaced broken lines depict parts of the printer that form no part of the claimed design. The dot-dash broken lines depict the bounds of the claimed design that form no part of the claimed design.

1 Claim, 7 Drawing Sheets
